(57) **CLAIM**

The ornamental design for a triple position umbrella stand, as shown and described.

DESCRIPTION

FIG. 1 is a perspective view of a triple position umbrella stand of the present design;

FIG. 2 is a top view thereof;

FIG. 3 is a front view, the back view being a mirror image thereof;

FIG. 4 is a bottom view thereof; and,

FIG. 5 is a right side view, the left side view being a mirror image thereof.

The back view is a mirror image of FIG. 3, and the left side view is a mirror image of FIG. 5.
